UNITED STATES PATENT OFFICE.

PERCY WALTER DRUITT AND WILLIAM ROBERT GILPIN, OF LONDON, ENGLAND.

TYPOGRAPHIC MACHINE.

1,419,030.

Specification of Letters Patent. Patented June 6, 1922.

Application filed October 12, 1920. Serial No. 416,529.

To all whom it may concern:

Be it known that we, PERCY WALTER DRUITT and WILLIAM ROBERT GILPIN, both subjects of the King of Great Britain, and 5 residing in London, England, have jointly invented certain new and useful Improvements in Typographic Machines, of which the following is a specification.

This invention relates to typographic machines of the character in which loose matrices contained in a magazine are assembled in line by keyboard mechanism, transferred after justification to a casting mechanism, separated and presented singly to a mould, 15 and a justified line of individual types produced therefrom.

The object of this invention is to increase the productive capacity of such machines by the employment of character matrices 20 each having more than one separately usable character indented on the same working face, as for example, the ordinary body character, and, in addition, the corresponding italic letter, small capital or other secondary 25 character or characters.

The kind of typographic machine to which the present invention is particularly applicable has been described in the specifications of British Patents Nos. 1903 of 1900 and 30 11870 of 1913, and the part of the such machines which is involved is the mechanism for presenting the matrices to the mould for casting purposes, such mechanism being modified by this invention so as to present the 35 matrix to the mould in the position appropriate to the particular character on the matrix which it is desired to reproduce in type.

With this object the presentation plunger or a part thereof is made capable of movement not only longitudinally or in a horizontal direction, but also transversely or in a vertical direction.

The invention will be described with reference to the accompanying drawings as applied to matrices having two characters indented in vertical relation with each other on the working face. In these drawings Fig. 1 is a front elevation of the essential part of a typographic machine of the kind 45 herein referred to, with the cover removed and parts shown in section; Fig. 2 is an end elevation of part of Fig. 1, with the mould removed; Fig. 3 is a section on line 3—3 of Fig. 1; Fig. 4 is a part view of Fig. 2, but 50 with a controller in place of ordinary ma-

trix in front of the presentation plunger; and Fig. 5 is a plan view of Fig. 1 with the mould partly in section.

With two character matrices there are two possible casting positions of the matrix determined by the position of an arresting stop b^0 which co-operates with a vertically 60 slideable head a^1 on the presentation plunger a . For example, for the lower of the two casting positions the head a^1 of the plunger, 65 impelled downwards by suitable sprung urged linkage, may engage a fixed aligning stop c^0 on the mould, while for the higher casting position it is arrested at the higher 70 level by an aligning bar b carried by the plunger a and projected to interpose the arresting stop b^0 between the mould stop c^0 and the plunger head a^1 . The change from 75 one position to the other is automatically effected as a consequence of the introduction 80 by the operator of a controller or matrix blank d into the line of matrices at the point at which the change is desired as hereinafter described. In the rearward position of the presentation plunger a , the plunger head a' 85

is always aligned with the separation channel e to receive the matrices therefrom, and upon the return of the presentation plunger after the casting operation, the downward pressure, due to spring f^0 acting through 85 lever f on the plunger head a' , is released to enable the latter to be returned automatically (if necessary) to vertical alignment with the separation channel. This return is effected by engagement of the inclined tail 90 f' of the lever f with a preferably adjustable stop g on the frame of the machine.

Accurate alignment of the head of the presentation plunger with respect to the separation channel is effected by means of a chamfered projection a^2 on the head of the presentation plunger entering a notch e' in the lower bar of the separation channel.

In general practice it will happen that most of the matrices will be used at the 100 higher level, i. e. that at which the primary or most commonly used characters are in the casting position. In this case the head a' of the presentation plunger a will move to and from the mould without any sensible 105 vertical movement. In the case of the secondary characters being used the plunger head a' and with it the matrix will be moved downwards in its passage to the mould c by an amount equal to the vertical distance 110

between the two characters and upwards again on its return to the separation channel.

For effecting these objects the aligning bar *b* is slidably mounted in the main body of the presentation plunger *a* and travels with it in such a way that although normally the aligning bar is in the forward position in which it is interposed between the aligning stop *c*^o of the mould *c* and the under side of the head *a'* of the plunger when the latter is against the mould, it is adapted, when desired to produce a secondary character, to be moved rearwardly, in which case under the pressure of the spring-urged linkage previously referred to and consisting of the compression spring *f*^o, spring-urged plunger *f*² and lever *f*, the head of the plunger will be lowered until it contacts directly with the aligning stop *c*^o of the mould.

The foregoing movement of the aligning bar and the selection of either its forward or rearward position, according to whether a primary or secondary character is required, is accomplished in the following manner.

The aligning bar *b* is urged by a spring *b'* rearwardly on to a cam *h* mounted on the body of the presentation plunger *a* and with the aligning bar *b* partaking of its reciprocating movement, the cam moving with the presentation plunger and also the aligning bar which, however, has an independent movement controlled by the cam. Mounted coaxially with the cam *h* and fastened to it is a ratchet disc *h'* having as many teeth *h*² as there are projections and depressions on the cam. A rotary movement of the ratchet *h'* tooth by tooth will cause the aligning bar to be alternately moved forward and retracted. A ratchet pawl *i*^o mounted on a slide *i* which receives motion from the cam shaft *j* driving the presentation plunger and co-operating parts is adapted to impart this rotary movement to the ratchet wheel *h'* and cam *h* when the latter is in a position corresponding with the rearward position of the presentation plunger. Further, the cams *h*, *l* controlling the movements of the presentation plunger and the ratchet pawl slide respectively are in such timed relationship that during the free reciprocation of the presentation plunger movement is imparted to the ratchet slide *i* only when the presentation plunger is in its forward position, and consequently in the normal working of the machine no relative movement is imparted to the aligning bar *b*, and primary or secondary letters will continue to be cast according to whether the aligning bar *b* is in its forward or rearward position as previously explained.

Whenever it is necessary, in the course of composition, to change from one face or font to another, the operator by means of a

finger key, assembles a controller *d* in the line of matrices at the point where the change is desired. These controllers, which are contained in a channel in the matrix magazine, are of metal and are similar in configuration and thickness to the matrices, except that they contain no character and have one of their lugs or ears—preferably that at the lower right hand corner *d*^o—of increased height.

The controller *d*, having been separated in due course and pushed into the head *a'* of the presentation plunger, now co-operates by means of its abnormal lug *d*^o with a projection *e*² on the adjacent rail of the separation channel in such a manner that the presentation plunger *a* is held stationary against the action of the spring *k*^o acting on the cam lever *k'* impelling it towards the mould. Under these conditions, as previously explained, the ratchet pawl *i*^o will engage with the ratchet wheel *h'* and present either a projection or a depression of the cam *h* to the aligning bar *b*, the position of which will be altered correspondingly. It will thus be seen that the insertion of a single controller into the line of matrices is all that is required to bring about the required change in character to be cast.

It is to be understood that during the cycle of the machine in which the presentation plunger is held inoperative by the controller, the movable blade of the mould, which may be constructed according to the patent specifications previously mentioned, will in the absence of a matrix on the face of the mould, completely close the aperture of the mould, thus effectually preventing any splashing of the metal.

Having thus described the nature of the invention and the best means we know of carrying the same into practical effect, we claim:

1. In typographic machines of the kind herein referred to, the combination with a type mould of character matrices each having more than one separately usable character on the same working face, means adapted to present each matrix to the mould in position to effect the casting of any one of the characters and means comprising a blank matrix or controller introduced into the line of matrices operating to determine which of said characters is presented in the casting position.

2. In typographic machines of the kind herein referred to, the combination with a type mould of a multiple character matrix and means for presenting said matrix to the mould in alternative positions, said means comprising a presentation plunger having a transverse movement as well as a longitudinal movement.

3. In an apparatus as claimed in claim 2, a presentation plunger having a head trans-

versely movable thereon, a mould having an aligning stop cooperating with the head of the presentation plunger, an aligning bar slidably mounted on said plunger and adapted to be interposed between the head of the presentation plunger and the aligning stop, and means operating to withdraw the aligning bar and permit the head of the presentation plunger to abut directly on the aligning stop.

4. In typographic machines of the kind herein referred to, the combination with a type mould of a multiple character matrix and means for presenting said matrix to the mould in alternative positions, said means comprising a presentation plunger having a head transversely movable thereon, means for reciprocating the presentation plunger longitudinally, a mould stop cooperating with the transversely movable head of the presentation plunger to arrest the character matrix carried thereby in one of the said alternative positions, and means carried by the presentation plunger and cooperating with the mould stop to arrest the character matrix carried by the presentation plunger in another of the said alternative positions.

5. In typographic machines of the kind herein described, the combination with a type mould of a multiple character matrix and means for presenting said matrix to the

mould in alternative positions, said means comprising a reciprocating presentation plunger, a transversely movable head on said presentation plunger adapted to carry the matrix, a stop reciprocating with the presentation plunger and normally operating to arrest the transversely movable head of the plunger, means operating to withdraw said stop out of engagement with said head when the forward movement of the presentation plunger is arrested, a blank matrix or controller adapted to be introduced into the line of matrices, and a stop adapted to engage the controller and arrest the forward movement of the presentation plunger.

6. In typographic machines of the kind herein described, the combination with a type mould of a multiple character matrix and means for presenting said matrix to the mould in alternative positions, said means comprising a stop normally operative to arrest the matrix in one of said positions, a blank matrix adapted to be introduced into the line of matrices, and means for changing the position of said stop controlled by said blank matrix.

In testimony whereof we have signed our names to this specification.

PERCY WALTER DRUITT.
WILLIAM ROBERT GILPIN.
